UNITED STATES PATENT OFFICE.

FRANK HUGH WADDILL, OF NEW ORLEANS, LOUISIANA.

LEVEE-REINFORCEMENT AND PROCESS OF MAKING THE SAME.

1,095,249.

Specification of Letters Patent.

Patented May 5, 1914.

Application filed June 23, 1913. Serial No. 775,387.

To all whom it may concern:

Be it known that I, FRANK H. WADDILL, a citizen of the United States, residing at New Orleans, in the parish of Orleans and 5 State of Louisiana, have invented a new and useful Levee-Reinforcement and Process of Making the Same, of which the following is a specification.

The present invention relates to improvements in reinforcements for levees and the process of making the same, one object of the present invention being the provision of a spinal reinforcement for the upper banks or levees of a river, or other body of water, 10 which will prevent the percolation of water through either the interstices of the material of the levee or through the holes or burrows of rodents or other destructive animals, the process for constructing such 15 spinal reinforcement being a continuous one, by means of which a free "running" concrete is employed in combination with a novel form of chamber or receptacle forming means to fill the cavity or chamber from 20 the bottom upwardly due to the hydrostatic pressure of the liquid running concrete.

A further object of the present invention is the provision of a novel form of chamber or channeling forming means adapted to 25 be driven centrally of the levee, the same producing a wedge-shaped cavity, whereby the respective driven elements may be removed one at a time as the liquid concrete is 30 poured and left in the ground.

A still further object of the invention is the provision of various shaped wedges which will permit of the work being readily resumed after a delay, as for instance, where the material runs short or the work is shut 35 down for repairs or over night, without disturbance to the concrete already deposited in place and set, the driven wedges in this state maintaining the concrete previously 40 poured in proper position and form for coalescence.

A still further object of the invention is the provision of various shaped wedges which will permit of the proper molding or 45 formation of a concrete receiving cavity according to the general contour or running shape of the levee, so that various turns either at acute, right angles or obtuse angles may be formed.

With the foregoing and other objects in 50 view which will appear as the description

proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a perspective view of the concrete reinforcement and the chamber forming wedges in proper position, the levee being shown in dotted lines. Fig. 2 is a cross section through a levee with the present reinforcement properly positioned therein, showing however, the concrete reinforcement carried above the crown of the levee by the use of ordinary moldboards. Figs. 3, 4 and 5 are detailed end views of various shaped wedges and core formers used in connection with the present invention. Fig. 6 is a perspective view of one of the wedge shaped members *per se*.

Referring to the drawings, the numeral 1 designates a lake, reservoir, stream or river bank, which has thrown thereupon the levee, earth embankment or dike 2, the same in the present instance, as will presently appear, being provided with a reinforcing concrete spine or wall A, which is formed with the material of the bank 1 and the embankment 2.

In putting the present invention into practice, a plurality of core forming wedges or driving elements 3 are provided, all of such elements being tapered in cross-section so as to form a slot in the embankment 2 and bank 1 of the shape as illustrated in Fig. 2 for the reception of the concrete or spine A, the same being of such a length as to, when driven, extend above the upper face of the levee or dike 2, where it is provided with an aperture to accommodate a pin (not shown) to permit of the ready withdrawing of the wedges 3 when desired, and as will presently appear.

The wedges 3 are driven, as clearly shown in Fig. 1, and after a certain number, as for instance 10, have been driven, the first wedge is pulled upwardly and the cavity formed thereby is filled with a free running concrete, preferably composed of sand, gravel and Portland cement, which may or may not be reinforced with steel. While the concrete in the core thus formed is still

in a liquid state, the next succeeding wedge 3 is gradually withdrawn, the withdrawal of the same opening the cavity first at the bottom, so that the liquid concrete previously 5 poured in the cavity formed by the first removed wedge will flow below the end of the wedge as the same is drawn upwardly, thus automatically, under hydrostatic pressure, filling the cavity from the bottom upwardly and preventing any voids that would often occur when the material is poured from above, and wedges intermediate of the ends of the cavity thus formed, which is often the case where the concrete used is of plastic 10 instead of free running consistency.

In order to provide a means for properly assembling the wedges 3, the same are provided with one beveled edge *d* at the bottom, so that in driving each, will, by reason thereof 20 of, be forced into close juxtaposition with the last previously driven, and are also provided with grooves *b* and tongues *c*, which coact with the adjacent wedges upon each side thereof and thus insure the proper alining of the next driven wedge downwardly in the dike or levee 2 and also provide a means to assist in the stability of the wedges when in the position, as shown in Fig. 1, which illustrates the wedges at the end of a 30 day's work, when it is necessary to shut down. In this case, three wedges 3', 4 and 6 are employed, the wedge 6 being provided with its two axial edges, 5 and 9, inclined, constituting in effect a double wedge, while 35 the wedge 4, is provided with an inclined edge 7, adapted to be disposed co-extensive with the edge 5 of the wedge 6, and the wedge 3' is provided with an inclined edge 8, adapted to be disposed co-extensive with 40 the edge 9, of the wedge 6, thus providing a means whereby, upon a resumption of the work after a delay, the wedge 6, may be first easily withdrawn, after which the wedge 4, is withdrawn, by which means the concrete 45 in place and set is not disturbed by the violence which it would be necessary to employ, in order to withdraw, 4, were the special shaped wedges 3', 4 and 6 not employed. Thus at the beginning of the work, 50 the next day, the wedge member 6 is primarily removed, thus permitting the wedge 4 to be readily removed and the cavity formed by the wedges filled as previously stated.

55 During the progress of the work, the first and succeeding wedges that are withdrawn are carried and driven in the dike or levee 2 adjacent the last driven wedge, so that the act of driving is continuous, while the act 60 of pouring the liquid concrete is also continuous, thus providing a means whereby a plurality of gangs of men may be working at the same time, one delivering and pouring the cement, one driving and the other pulling the wedges, the work being practically

continuous, so that where the spinal reinforcement is placed in position upon work with the proper amount of material at hand, there is no necessity for halting the pouring of the concrete until the same is completely 70 formed, thus making a continuous job or operation without any breaks in the walls as the single wall would be an integral concrete member from one end to the other.

As is often the case, when the levee or 75 dike has an irregular form, according to the outline of the bank of the stream or river, the wedge 3 must be made to accommodate the same, so that the spinal reinforcement may be disposed as near the center as possible. For this purpose, the wedges 10, 10' and 11 are provided, the wedge 10 being employed when the reinforcement is turned to the right as for instance, while the wedge 10' is employed where the reinforcement is to be turned to the left. In the 80 form of reinforcement wedge shown in Fig. 5, the same is used where the bank turns abruptly at right angles, at which time the wedge member 11 provides a cavity for the 85 reinforcement as a corner post.

Where the spinal reinforcement is upon the levee which is desired to have a projection thereabove, as shown in Fig. 2, any 90 form of mold boards for forming the upper 95 projecting end of the same is provided, the same being applied and positioned as the wedges are withdrawn and the fluid concrete poured, or may be primarily positioned leaving sufficient space to permit of the driv- 100 ing and withdrawal of the wedges.

What is claimed is:

1. The herein described process of reinforcing a levee or embankment, consisting in successively driving one at a time, a plurality of interlocking core forming wedge shaped members, withdrawing the first one, filling the void formed with a free running concrete, and alternately withdrawing a core member and filling the void with a free running concrete, whereby the void below the core member during its withdrawal will be filled from the bottom upwardly with the concrete from the void previously filled, due to the hydrostatic pressure of the concrete 110 in such void.

2. The herein described process of reinforcing a levee or embankment, consisting in successively driving a plurality of core-forming wedge-shaped members and alternately withdrawing a member, and filling the void with a free running concrete.

3. The herein described process of producing a spinal reinforcement for levees or embankments, consisting in successively driving a plurality of core-forming wedge-shaped members, alternately withdrawing one member at a time and filling the void thus formed from the top with a free running concrete, whereby each successive void 125 130

is filled due to the hydrostatic pressure of the concrete from a point below the core member being withdrawn.

4. A core-forming and retaining means for a spinal reinforcement of a levee, including a plurality of wedge-shaped interlocking driven members, and three wedge-shaped members to be driven between the freshly poured concrete and the first members, the outer members of which are provided with outer edges in parallel to each other while the inner edges are dis-

posed to taper from the lower end to the top, the intermediate member being tapered both transversely and laterally for wedging 15 engagement with the two adjacent members.

In testimony that I claim the foregoing as my own, I have hereto affixed my signature in the presence of two witnesses.

FRANK HUGH WADDILL.
